Technical cross-sectional diagram of a mechanical assembly, likely a pump or valve, with various numbered components labeled 1 through 23. The diagram shows a central vertical assembly with a piston-like component at the top, connected to a rod, and surrounded by various mechanical parts and a base structure. The components are labeled as follows:

- 1
- 2
- 3
- 4
- 4^a
- 5
- 6
- 7
- 8
- 9
- 10
- 11

UNITED STATES PATENT OFFICE.

LANSING ONDERDONK AND AUGUST J. WOHLPART, OF NEW YORK, N. Y., ASSIGNEES TO UNION SPECIAL MACHINE COMPANY, OF CHICAGO, ILLINOIS, A CORPORATION OF ILLINOIS.

FEEDING MECHANISM FOR SEWING MACHINES.

Application filed April 8, 1922. Serial No. 550,883.

To all whom it may concern:

Be it known that we, LANSING ONDERDONK and AUGUST J. WOHLPART, citizens of the United States, both residing at New York, in the county of New York, State of New York, have invented certain new and useful Improvements in Feeding Mechanisms for Sewing Machines, of which the following is a description, reference being had to the accompanying drawing and to the figures of reference marked thereon.

The invention relates to new and useful improvements in feeding mechanisms for sewing machines, and more particularly the feeding mechanism adapted to be used in connection with a sewing machine having a work support in the form of a vertically extending post.

An object of the invention is to provide a feeding mechanism for the post machine which includes a main feed dog and an auxiliary feed dog, and wherein provision is made for giving said feed dogs a differential movement.

Another object of the invention is to provide a differential feeding mechanism of the above type wherein the auxiliary feed dog derives all its movements from the main feed bar supporting and operating the main feed dog.

A further object of the invention is to provide a feeding mechanism of the above type, wherein the throw of the auxiliary feed dog may be varied.

These and other objects of the invention will in part be obvious and will in part be hereinafter more fully disclosed.

In the drawings:—

Figure 1 is a vertical sectional view through a portion of a sewing machine showing the feeding mechanism in side elevation;

Fig. 2 is a vertical sectional view through a portion of the work support showing the feeding mechanism as viewed from the rear of the machine;

Fig. 3 is a top plan view of the throat plate and showing the arrangement of the feed dogs;

Fig. 4 is a view similar to Fig. 1, but showing a modified form of arrangement for operating the auxiliary feed dog;

Fig. 5 is a view similar to Fig. 2, but showing the modified form of mechanism for actuating the auxiliary feed dog; and

Fig. 6 is a sectional view on the line 6—6 of Fig. 5.

The machine in which the invention is embodied is of the work supporting post type, such as shown in the Onderdonk prior Patent No. 1,129,591, patented February 23, 1915. The machine includes a supporting frame 1 at the forward end of which is a work supporting post 2. This work supporting post 2 carries a throat plate at the upper end thereof, and the material being stitched rests upon said throat plate. All the parts within the work supporting post are operated from an actuating shaft 3 mounted in the supporting frame. This shaft rotates and carries at its forward end suitable eccentrics 4 and 4^a for operating the feeding mechanism.

The main feeding mechanism consists of a main feed bar 5 which is provided with a yoke 7 at the upper end thereof, and mounted upon the yoke is a main feed dog 6. The lower end of the feed bar 5 is pivotally mounted upon a lever 8, which lever 8 is in turn pivoted at 9 and is oscillated by the eccentric 4^a. As this lever 8 is raised and lowered, it will raise and lower the feed bar, moving the feed dog 6 carried thereby into and out of engagement with the material. The feed bar 5 is oscillated back and forth on its pivotal attachment to the lever 8 by means of a lever 10. The lever 10 at its lower end engages the eccentric 4^a so that, as the shaft 3 rotates, the lower end of this lever will move in a circular path. The lever 10 is pivoted to a link 11 which in turn is pivoted to an arm 12 carried by a bracket member which may be adjusted for varying the position of the arm 12, and thus varying the length of feed stroke. The upper end of the lever 10 is connected by a link 13 to the feed bar.

It will readily be seen that, inasmuch as the lever 10 is pivoted intermediate its ends to the link 11 and the pivotal support for the link 11 is below the pivotal connection between said link and the lever, the upper end of the lever will move in a curved path back and forth, and this curved path is

so disposed that the upper end of the lever has an up and down movement as well as a back and forth movement. Thus it is that the feed bar is oscillated back and forth on its pivotal connection with the lever 8.

The above parts are all similar in construction and operation to those shown in the prior patent referred to and will not need further description.

10 There is also provided an auxiliary feed dog 14. Said auxiliary feed dog 14 is carried by a yoke 15, which yoke is pivotally supported by the pivot pin 16, which pivot pin connects the link 13 to the main feed dog. The yoke 15 has a downwardly extending arm 17, said arm having a vertically extending groove or recess 18 adapted to receive the square bearing block 19 mounted on a pin 20, and this pin 20 is provided 20 with a collar 21 and a thumb nut 22. The pin extends through a slot 23 in the post and can be adjusted up and down in said slot.

It will readily be seen that, as the main feed bar is moved back and forth and up 25 and down, the yoke 15 carrying the auxiliary feed dog will be similarly moved back and forth and up and down, as said yoke is pivoted on the pivot pin 16 which partakes of all the movements of the feed bar 30 5. As the pivot pin 16 moves bodily to the left or the right, as viewed in Fig. 1, the arm 17, which is rigid with the yoke, will have no sidewise movement as it engages the pin 20 which is stationary. Therefore, 35 when the pivot pin 16 moves back and forth to impart feeding movements to the main feed dog, the auxiliary feed dog will be moved back and forth thereby but to a greater distance.

40 The reason that the auxiliary dog is moved a greater distance is due to the fact that the pivot pin 20 on which the auxiliary feed bar oscillates as a fulcrum is nearer to the pivot pin 16 than the pivotal connection between the lower end of the main feed bar and the lever 8. The pivot pin 20 is the fulcrum for the swinging of the auxiliary feed bar which consists of the yoke 15 and depending arm 17. By shifting the 45 pin 20 in the slot in the post, the extent of additional movement imparted to the auxiliary feed dog may be varied. By the arrangement described, the auxiliary feed dog will be moved to a greater extent than the 50 main feed dog for all adjustments of the pin 20. The auxiliary feed dog is located in advance of the main feed dog and operates in the usual well-known manner to gather in the material in advance of the 55 needles.

In the modification shown in Figs. 4, 5 and 6, the means for operating the main feed bar and the feed dog carried thereby is the same as described above and as shown in 60 the prior patent. There is, however, shown

a slightly modified form of means for imparting the additional movement to the auxiliary feed dog.

The auxiliary feed dog 14 is carried by a yoke 15 and this yoke is provided with a 70 depending arm 17 which, together with the yoke, forms the auxiliary feed bar. A rock lever 24 is pivotally mounted upon a stud 25 secured to the post of the machine. Said rock lever 24 has a depending slotted arm 26 75 and a laterally extending forked arm 27. On the upper end of the lever 10 there is a square block 28 which slides in the forked arm 27. This square block 28 is mounted on a pivot pin which connects the lever 10 80 to the link 13. The depending arm 26 is slotted, and adjustably mounted in the slot 85 is a pin 29. The arm 17 is provided with a groove or recess 30 into which the pin 29 extends.

As the lever 10 is oscillated by the rotating of the eccentric 4, the upper end thereof, as above noted, moves in a curved path having horizontal and vertical components so that on each oscillation of the lever 10 the pin carrying the block 28 will have a vertical movement as well as a horizontal movement, and this will cause the rock lever 24 to oscillate on its pivotal support. The oscillation of the rock lever through the pin 29 will give an additional movement to the auxiliary feed bar and to the auxiliary feed dog carried thereby. If the pin 29 is adjusted to a point so that its extent of movement 95 is the same as the extent of movement of 100 the pin 16 on which the auxiliary feed dog is mounted, then the auxiliary feed dog will have the same extent of movement as the main feed dog. When the pin 29 is moved upwardly, however, the extent of movement 105 imparted thereto will be less, and this will, of course, increase the extent of additional movement imparted to the auxiliary feed dog.

It will be noted from the above that there 110 is provided a very simple means for imparting movements to the auxiliary feed dog, said movements all being derived from the movements of the main feed bar. There is also provided a means wherein the 115 extent of movement imparted to the auxiliary feed bar may be readily varied to suit the conditions under which the machine is operating.

It is obvious that minor changes in the 120 details of construction may be made without departing from the spirit of the invention as set forth in the appended claims.

Having thus described the invention, what 125 is claimed as new is:—

1. A sewing machine including in combination, a supporting frame, a work supporting post extending vertically therefrom, a main feed dog, a feed bar extending vertically of the work supporting post on which 130

said main feed dog is mounted, means for raising and lowering said main feed bar and for oscillating the feed bar imparting to the feed dog its movements, an auxiliary feed dog, and devices actuated from the main feed bar for imparting movements to said auxiliary feed dog.

2. A sewing machine including in combination, a supporting frame, a work supporting post extending vertically therefrom, a main feed dog, a feed bar extending vertically of the work supporting post on which said main feed dog is mounted, means for raising and lowering said main feed bar and for oscillating the feed bar imparting to the feed dog its movements, an auxiliary feed dog, and devices actuated from the main feed bar for imparting movements to said auxiliary feed dog, said devices being constructed so as to give to said auxiliary feed dog a movement of greater extent than that imparted to the main feed dog.

3. A sewing machine including in combination, a supporting frame, a work supporting post extending vertically therefrom, a main feed dog, a main feed bar extending lengthwise of said post and carrying said main feed dog, means pivoted to the lower end of said main feed bar for raising and lowering the same, means connected to the feed bar intermediate its ends for oscillating the same for moving the feed bar back and forth, an auxiliary feed dog, devices movable with the main feed bar for supporting said auxiliary feed dog, and means for giving said devices a movement in addition to the movement imparted thereto by the main feed bar.

4. A sewing machine including in combination, a supporting frame, a work supporting post extending vertically therefrom, a main feed dog, a feed bar extending lengthwise of the post and carrying said main feed dog, means pivoted to the lower end of the feed bar for raising and lowering the same, means connected to the feed bar intermediate its ends for oscillating the feed bar and giving back and forth movements to the main feed dog, an auxiliary feed dog, devices movable with the main feed bar for supporting said auxiliary feed dog, adjustable means connected to said devices whereby the movements imparted by the main feed bar to the auxiliary feed dog increase.

5. A sewing machine including in combination, a supporting frame, a work supporting post extending vertically therefrom, a main feed bar extending lengthwise of the post, a main feed dog rigidly connected

thereto, an auxiliary feed dog movably mounted on the main feed bar, means for raising and lowering the feed bar and the feed dogs carried thereby, means for oscillating the feed bar and the feed dogs carried thereby, and devices engaging the supporting means for the auxiliary feed dog operating to increase the movements imparted thereto by the main feed bar.

6. A sewing machine including in combination, a supporting frame, a work supporting post extending vertically therefrom, a main feed bar extending lengthwise of the post, a feed dog rigidly carried thereby, means for raising and lowering the main feed bar, means for oscillating the feed bar, a yoke having a depending arm pivotally supported on the main feed bar, an auxiliary feed dog carried thereby, and adjustable means engaging said depending arm for oscillating the yoke on the main feed bar as the main feed dog oscillates.

7. A sewing machine including in combination, a supporting frame, a work supporting post extending vertically therefrom, a main feed bar extending lengthwise of the post, a feed dog rigidly carried thereby, means for raising and lowering the main feed bar, means for oscillating the feed bar, a yoke having a depending arm pivotally supported on the main feed bar, an auxiliary feed dog carried thereby, and adjustable means engaging said depending arm for oscillating the yoke on the main feed bar as the main feed dog oscillates, said devices being adjustable for varying the additional movement imparted to the auxiliary feed dog.

8. A sewing machine including in combination, a supporting frame, a work supporting post extending vertically therefrom, a main feed bar extending lengthwise of the post, a main feed dog rigidly carried thereby, means for raising and lowering the main feed bar, means for oscillating the feed bar, a yoke having a depending arm pivotally supported on the main feed bar, an auxiliary feed dog carried by the yoke, said post having a vertical slot therein, a pin adjustable in said slot and having engagement with the slot or recess extending lengthwise of the depending arm whereby, as the yoke is oscillated by movements of the main feed bar, said pin engaging said depending arm will not impart an additional movement to the auxiliary feed dog.

In testimony whereof, we affix our signatures.

LANSING ONDERDONK,
AUGUST J. WOHLPART.
